CHANGEABLE LETTER SIGN AND THE LIKE

Lodwick J. Wentzel, Brooklyn, N. Y.

Application December 31, 1937, Serial No. 182,649

8 Claims. (Cl. 40—140)

This invention relates to new and useful improvements in changeable letter signs.

More specifically the invention proposes the construction of a plate having a plurality of spaced slots dividing off strip portions between adjacent slots for supporting sign elements.

Still further the invention proposes the construction of a sign element which consists of a front portion extending transversely across each strip portion and having its bottom end portion engaging through the bottom slot of the strip portion, and its top end continuing through the top slot of said strip portion into a rear portion adapted to extend transversely across the back 15 of said strip portion with its bottom end adjacent the bottom end of said portion.

Still further it is proposed to provide a back plate which is adapted to extend across the back of said base plate for engaging against and holding the adjacent bottom end portions of said sign elements.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a changeable letter sign constructed according to this invention.

Fig. 2 is an enlarged sectional view taken on the line 2—2 of Fig. 1.

Fig. 3 is an enlarged sectional view on the line 3—3 of Fig. 1.

Fig. 4 is a perspective view of one of the sign elements per se.

Fig. 5 is a perspective view of a modification of the invention.

Fig. 6 is a sectional view on the line 6—6 of Fig. 5.

Fig. 7 is a sectional view on the line 7—7 of Fig. 5.

Fig. 8 is a view looking in the direction of the line 8—8 of Fig. 5.

Figs. 9—12 are perspective views of the discs, per se, used in conjunction with the form of the invention shown in Fig. 5.

Fig. 13 is a perspective view of a further modification of the invention.

Fig. 14 is a sectional view on the line 14—14 of Fig. 13.

Fig. 15 is a perspective view of the connected sign elements which are used in connection with the embodiment shown in Fig. 13.

Fig. 16 is a perspective view of still another modification of the invention.

The changeable letter sign, according to this invention, comprises a face plate 10 having a plurality of spaced slots 11 dividing off strip portions 12 between adjacent slots 11. A plurality of sign elements 13 are mounted on each strip portion 12. Each sign element 13 comprises a front portion 13^a extending transversely across the strip portion 12 with its bottom end portion 13^{aa} engaging through the bottom slot 11 of the strip portion 12 and a rear portion 13^b which continues through the top slot 11 of the strip 12 to the rear. This rear portion is adapted to extend transversely across the back of the strip 15 portion 12 and have its bottom end 13^{bb} adjacent the bottom end portion 13^{aa}. A back plate 14 extends across the back of the face plate 10 for engaging against and holding the bottom portions 13^{aa} and 13^{bb} of the sign elements 13.

The face plate 10 is constructed of a piece of sheet metal, or other similar material, and continues at its top edge into said back plate 14. This back plate is provided with a plurality of inwardly extending prongs 15 which are adapted 25 to engage against the back face of the end portion 13^{bb} for frictionally maintaining these ends in position between the front face 10 and the back face 14. The bottom ends of the face plate 10 and the back plate 14 are provided with 30 aligned openings 16 through which a bolt 17 is adapted to pass for fixedly holding these plates together. The closed position of the back plate 14 is illustrated by the dot and dash lines 14' in Fig. 2.

The operation of this device is as follows:—

The bolt 17 is removed from the openings 16 so that the back plate 14 may be swung away from the front plate 10 to permit those sign elements 13 now in position on the face plate to 40 be removed. After these sign elements have been removed they may be replaced by any combination of sign elements for producing any desired sign for advertising various articles of merchandise. After these sign elements have been properly positioned upon the strip portions 12 with the ends 13^{aa} and 13^{bb} thereof properly positioned, the back plate 14 is again swung to the position in which the prongs 15 will engage against the ends 13^{aa} and 13^{bb}. After this has 45 been completed the bolts 17 are engaged into the openings 16 for fixedly holding the plates 10 and 14 together to prevent the sign elements from being accidentally displaced therefrom.

According to the modification shown in Figs. 55:

5-12, inclusive, a face plate 10' is provided at its upper portion with a plurality of slots 11 dividing off strip portions 12 upon which sign elements 13 may be supported. The bottom portion of this 5 face plate 10' is formed into an envelope by doubling a portion thereof 10^a upon itself and attaching the edges thereof together so that the top 10^b thereof will be open. The bottom portion of the face plate 10' is provided with an 10 opening 18 and imprinted advertising matter 19. Superimposed discs 20 and 21 are adapted to be rotatively connected together by a pin 22 which passes through the center thereof. The top disc 20 is provided alternately with indicia 15 23 and openings 24, while the bottom disc 21 is only provided with indicia 25. Thus these discs may be rotated with relation to each other to make various combinations. After the desired combination has been found the discs 20 20 and 21 are adapted to be inserted in the envelope formed by the portion 10^a so that this combination will be viewable through the opening 18. Thus the combination of numbers will act to indicate the price of the merchandise which 25 is advertised by the printed matter 19. In other respects this form of the invention is similar to the previous form.

According to the modification shown in Figs. 13-15 inclusive a face plate 10'' is provided 30 with a plurality of slots 11 dividing off strip portions 12 upon which sign elements 13' are adapted to be supported. These sign elements 13' are connected together (see Fig. 15) and are adapted to be cut apart and folded on their 35 center line to produce the shape which is adapted to be hooked through the slots 11. The two faces of the sign elements 13' are imprinted with various markings 26 so that when they are put together they will form a picture. Thus 40 this form of the invention simulates a puzzle board rather than a sign. The back plate 14' is provided with a plurality of slits 27 on its two sides which divide off lugs 28 which are adapted to be passed through vertical slots 29 45 formed in the edge of the face plate 10'' for releasably connecting the back plate 14' to the face plate 10'' when the lugs 28 formed by the slits 27 are passed through the vertical slots 29. In other respects this form of the invention 50 is similar to the previous form.

According to the modification shown in Fig. 16, the face plate 10''' is provided with a rear pocket 10^{aa} into which discs 20 and 21 may be inserted for giving the price of the merchandise 55 advertised thereon. This face plate 10''' is provided with an opening 18 and a plurality of slots 11 dividing off separate strip portions 12 upon which sign elements 13 are adapted to be interchangeably mounted for advertising a desired commodity, the price of which will be 60 viewable through the openings 18. In other respects this form is similar to the form illustrated in Figs. 5-12 inclusive.

While I have illustrated and described the 65 preferred embodiments of my invention, it is to be understood that I do not limit myself to the precise constructions herein disclosed and the right is reserved to all changes and modifications coming within the scope of the invention 70 as defined in the appended claims.

Having thus described my invention, what I claim as new, and desire to secure by United States Letters Patent is:—

1. A changeable letter sign, comprising a face 75 plate having a plurality of spaced slots divid-

ing off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements. 10

2. A changeable letter sign, comprising a face 15 plate having a plurality of spaced slots dividing off strip portions between adjacent slots, a plurality of sign elements mounted on each strip portion, each sign element comprising a front 20 portion extending transversely across said strip portion and having its bottom end portion engaging through the bottom slot of said strip portion and its top end continuing through the top slot of said strip portion into a rear portion, said rear portion extending transversely 25 across the back of said strip portion and having its end portion adjacent said bottom end portion, and a back plate for extending across the back of said face plate for engaging against and holding the rear portions of said sign elements, 30 said back plate being provided with a plurality of inwardly extending prongs which are adapted to engage the bottom ends of said sign elements for frictionally holding these elements in position upon the strip portion. 35

3. A changeable letter sign, comprising a face 40 plate having a plurality of spaced slots dividing off strip portions between adjacent slots, a plurality of sign elements mounted on each strip portion, each sign element comprising a front 45 portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, 50 and means for clamping said plates together.

4. A changeable letter sign, comprising a face 55 plate having a plurality of spaced slots dividing off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, and means for clamping said plates together, comprising bolts engageable through aligned openings formed in 60 said face plate and said back plate for clamping said plates together. 65

5. A changeable letter sign, comprising a face 70 plate having a plurality of spaced slots dividing off strip portions between adjacent slots, a plu- 75

- 5 rality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, and means for clamping said plates together, comprising lugs 10 formed on said back plate which are adapted to engage through slots formed in said face plate for holding these plates together.

15 6. A changeable letter sign, comprising a face plate having a plurality of spaced slots dividing 20 off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, said sign elements comprising letters, symbols, pictures, or portions of pictures, and puzzles.

25 7. A changeable letter sign, comprising a face plate having a plurality of spaced slots dividing 20 off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, said sign elements comprising letters, symbols, pictures, or portions of pictures, and puzzles.

30 8. A changeable letter sign, comprising a face plate having a plurality of spaced slots dividing 25 off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, said sign elements comprising letters, symbols, pictures, or portions of pictures, and puzzles.

35 9. A changeable letter sign, comprising a face plate having a plurality of spaced slots dividing 30 off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, said sign elements comprising letters, symbols, pictures, or portions of pictures, and puzzles.

40 10. A changeable letter sign, comprising a face plate having a plurality of spaced slots dividing 35 off strip portions between adjacent slots, a plurality of sign elements mounted on each strip portion, each sign element comprising a front portion extending transversely across said strip portion and having its bottom end portion engaging through the bottom slot of said strip portion and its top end continuing through the top slot of said strip portion into a rear portion, said rear portion extending transversely across the back of said strip portion and having its end portion adjacent said bottom end portion, and a back plate for extending across the back of said face plate for engaging against and holding the rear portions of said sign elements, said sign elements comprising letters, symbols, pictures, or portions of pictures, and puzzles.
